[57] CLAIM

The ornamental design for a toggle switch guard, as shown and described.

DESCRIPTION

FIG. 1 is an enlarged perspective view of a toggle switch guard showing my new design;

FIG. 2 is a side elevational view taken from the right of

FIG. 1, the side opposite being a mirror image thereof;

FIG. 3 is a front elevational view thereof;

FIG. 4 is a top plan view thereof;

FIG. 5 is a bottom plan view thereof; and,

FIG. 6 is a rear elevational view thereof.
